UNITED STATES PATENT OFFICE.

ELLIS C. DE CAMP, OF CINCINNATI, OHIO, ASSIGNOR TO THE WILLIAMSON HEATER COMPANY, OF CINCINNATI, OHIO, A CORPORATION OF OHIO.

CLOTHES DRIER.

Application filed June 27, 1923. Serial No. 648,034.

An object of my invention is to provide a simple laundry drier wherein an even distribution of heat may be obtained.

Another object of my invention is to provide a device of the type referred to wherein the burners may be disposed at one end of the device, yet, wherein, the same high degree of efficiency may be attained from all parts of the device.

Another object is to provide a structure for relieving pressure and temperature below the heating chamber of such device and to provide additional air for combustion.

Another object is to provide means for creating a more effective circulation of the heated air.

These and other objects are attained by means described herein and disclosed in the accompanying drawing, in which:

Fig. 1 is a perspective view of a drier embodying my invention.

Fig. 2 is a fragmental transverse sectional view of the device shown in Fig. 1.

Fig. 3 is a plan view of a distributor plate forming a detail of my invention.

Fig. 4 is a sectional view on line 4—4 of Fig. 3.

Fig. 5 is a sectional view on line 5—5 of Fig. 2.

The casing 5 comprises angle plates 6 forming the corners of a rectangular structure between which extend suitable front, side and back plates 7, 8 and 9 respectively, the plates forming vertical closures for the device. A suitable cover 10 forms a lid or top for the case. The lower ends of the front and back plates are inturned whereby to form flanges 11 and 12 supporting the cross bars 13 upon which cross bars, is mounted a bottom pan or plate 14 and supports 15. Suitable burners 16 are mounted on the burner supports 15 and extend approximately one third of the length of the casing. The plates 7 and 9 have mounted on them suitable plates 17 removably supporting a deflector plate 18, and T bars 19 mounted on the deflector plate removably support a screen 20 above the deflector plate. The deflector plate is divided, lengthwise, into substantially three portions. The portion 28 has a series of perforations 21 which extend in single rows along its opposite sides. The portion 29 immediately adjacent the last referred to portion, or in other words, the intermediate portion of the de-

flector plate has several rows of perforations 22 extending substantially parallel with the side edges of a deflector plate, the perforations extending inwardly a short distance from the side edges of the deflector plate whereby an imperforate center portion 23 is provided. The third section 30 of the deflector plate is located at the end of the deflector plate and is spaced from the first mentioned portion of the deflector plate by the intermediate portion thereof. The last mentioned portion of the deflector plate has spaced perforations 24 throughout its entire length and width. The bottom plate has upturned flanges 25 formed along its opposite side edges, whereby a flow of air from the outside of the casing may enter the chamber 26 formed between the deflector plate and the bottom plate, the flanges also serving to preclude light rays and heat waves from passing between the bottom and the casing, thereby avoiding burning and scorching of the floor supporting the device. The bottom is provided with a few apertures 31 immediately below the burners for admitting oxygen to the burners.

By taking the oxygen from beneath the bottom plate 13 through the apertures 31, the temperature and external pressure on the bottom plate, caused by heating the air or atmosphere intermediate the bottom plate and the floor which supports the drier, is relieved. If the air intermediate the bottom plate and the floor is not permitted to escape, or if means are not provided to draw off the heated air, the air would soon become exceedingly hot and would exert a damaging pressure on the bottom plate. The apertures 31 allow this heated air to pass into the heating chamber 26 where it is further heated and passed up into the drying chamber, while cool air replaces the air withdrawn from below the bottom plate, thereby keeping the plate relatively cooler and precluding scorching of the floor.

The deflector plate carries a depending baffle plate 32. The baffle plate is of a substantially U shape and has its arms or branches secured upon the lower face of the deflector plate. A passage or air channel 34 is formed between the baffle and the deflector plate. The channel is open at its ends and underlies the portion 28 of the deflector plate, thereby precluding overheating of the deflector plate immediately over the burners.

and at the same time creating a positive flow of hot air lengthwise of the deflector plate for effecting an even distribution of heat. By creating an air current in the heating chamber, auxiliary to the current directly created by the products of combustion, an intermingling of the air throughout the heating chamber is obtained. The relationship of the apertures in the deflector plate together with this equalization of temperature in the heating chamber causes an equalization of heat in the drying chamber, the hotter portions of the deflector plate radiating heat sufficient to compensate for the larger flow of heated air into the drying chamber through the cooler portions of the deflector plate.

In the operation of my device, the burner being located below the first mentioned portion 28 of the deflector plate, this first mentioned portion of the deflector plate is considerably hotter than the two other portions thereof, notwithstanding the provision of the baffle and the air heating channel 34, wherefore the limited number of holes disposed along the side edges of the first portion provide an adequate flow of heated air to that portion of the drier immediately above the burners. The intermediate portion 29 of the deflector plate permits a larger flow of heated air into the laundry drier, and the third mentioned portion 30 of the deflector plate permits a practically unobstructed flow of air from the chamber 26 to the drying chamber 27 disposed above the deflector plate. The screen 20 serves to preclude scorching by the deflector plate of any articles which might fall from the hangers which are provided in the upper part of the chamber 27.

What I claim is:

1. In a laundry drier the combination of a casing having a heating chamber and a drying chamber, a perforated deflector plate dividing the chambers, burners in the heating chamber underlying part of the deflector plate, and a baffle plate intermediate the deflector plate and the burners for providing a channel for creating an air draft below the deflector plate.

2. The combination with a casing and burners adapted to generate heat within the casing, of a deflector plate mounted above the burners and dividing the casing into a drying chamber and a heating chamber, part of the deflector plate extending over the burners and having perforations formed in it, the perforations increasing in number as the plate recedes from the burner, the casing having a perforated bottom plate underlying the burners, the perforations therein relieving the external pressure and temperature on the bottom plate.

3. The combination with a casing and

burners adapted to generate heat within the 65 casing, of a deflector plate mounted above the burners and dividing the casing into a drying chamber and a heating chamber, part of the deflector plate extending over the 70 burners and having perforations formed in it, the perforations increasing in number as the plate recedes from the burner, and a baffle plate carried by the deflector plate above the burner, the baffle plate and the portion of the deflector plate having the 75 least perforations together providing a heating channel communicating at its end with the chamber containing the burners.

4. The combination with a casing and burners adapted to generate heat within the 80 casing, of a deflector plate mounted above the burners and dividing the casing into a drying chamber and a heating chamber, part of the deflector plate extending over the 85 burners and having perforations formed in it, the perforations increasing in number as the plate recedes from the burner, the casing having a perforated bottom plate underlying the burners, the perforations therein relieving the external pressure and 90 temperature on the bottom plate and a baffle plate carried by the deflector plate above the burners, the baffle plate and the portion of the deflector plate having the least perforations together providing a 95 heating channel communicating at its end with the chamber containing the burners.

5. In a device of the class described the combination of a casing having side walls and a heating chamber, burners in the heating chamber, and a bottom plate below the 100 burners having its ends spaced from the side walls of the casing and having flanges for intercepting light rays directed toward the space between the bottom plate and the side 105 walls of the casing, and having apertures below the burners for relieving the external pressure and temperature on the bottom plate.

6. In a device of the class described, the 110 combination of a casing, having walls and having a heating chamber and a drying chamber, a plate between the chambers, a burner in the heating chamber, extending 115 under part of the plate, the plate and the casing walls being arranged to provide a relatively small flow of heated gas from the heating chamber to the drying chamber adjacent the burner, and to provide a relatively 120 large flow of heated gas from the heating chamber to the drying chamber remote from the burner, and a baffle spacing the burner from the plate and providing an air passage between said baffle and plate.

In testimony whereof, I have hereunto 125 subscribed my name this 25th day of June, 1923.

ELLIS O. DE CAMP.
